UNITED STATES PATENT OFFICE.

JOHN H. TOMLINSON AND JAMES M. STARR, OF TERRE HAUTE, INDIANA.

LUBRICATOR.

SPECIFICATION forming part of Letters Patent No. 778,087, dated December 20, 1904.

Application filed May 4, 1904. Serial No. 206,355.

To all whom it may concern:

Be it known that we, JOHN H. TOMLINSON and JAMES M. STARR, both citizens of the United States, and residents of Terre Haute, 5 in the county of Vigo and State of Indiana, have invented a new and Improved Lubricator, of which the following is a full, clear, and exact description.

Our invention relates to lubricators, and 10 more particularly to those adapted for use in connection with crank-pins, eccentrics, and the like.

It has for its principal objects the provision 15 of a simple and effective device of this class.

It consists in the various features and combinations hereinafter described and more particularly claimed.

Reference is to be had to the accompanying 20 drawings, forming a part of this specification, in which similar characters of reference indicate corresponding parts in all the figures.

Figure 1 is a side elevation of a lubricator embodying one form of our invention. Fig. 25 2 is a central vertical section therethrough. Fig. 3 is a top plan view with the cover removed, and Fig. 4 is a horizontal section on the line 4 4 of Fig. 2.

C designates a receptacle or cup consisting 30 of a base 10, which may have hexagonal walls 11 to permit it to be grasped by a wrench, and a preferably cylindrical side wall 12. The upper portion of this wall 12 is shown as internally threaded at 13 to receive a screw- 35 cover 14. At the center of the base is a threaded opening through which extends a plug P, having a threaded portion 15 of maximum diameter for engagement with the opening. Outside of the cup-base the plug has a 40 portion 16, which is preferably threaded to serve as a stem for securing the lubricator in place, it being here illustrated as mounted upon an element E. The opposite end of the plug projects at 17 into the cup, and through 45 its inner face opens a feed-channel 18, extending through the plug. Surrounding this opening is formed a seat 19, with which may contact a movable member or ball 19^a, which when 50 in contact with said seat under the influence of gravity will close the channel.

The projection 17 is preferably threaded to engage a retaining member or cage 20, fitting over it and preventing the ball from moving far from its seat. Through the side wall of the cage are openings 21, situated above the 55 upper end of the block, thus leaving below them a small inner receptacle surrounding the ball-seat. From the cage rises an upward extension 22, through which is a vertical bore threaded to receive a screw or adjusting member 23. This screw is preferably provided with a milled head 24, situated above the top of the cup, to enable it to be conveniently turned, and with a lock-nut 25, contacting with the upper end of the extension and serving to secure the screw in place. The inner 60 end of the screw may have a curved concave surface at 26 of substantially the same contour as the surface of the ball. This limits the range of movement of the latter from its 65 seat. The inner wall of the cage above the seat is also shown as spherical to permit the ball to coat smoothly therewith when the screw is raised to give the extreme lift for maximum feed. 70

In use the cup is supplied with oil or a properly fluid grease, and when the parts to be lubricated are at rest the ball will coat with the seat and wholly prevent the entrance of the lubricant into the feed-passage; but when 75 the parts are in motion—as, for example, that of an eccentric—the centrifugal force generated by their throw will cause the ball to rise until it contacts with the adjusting-screw, thus opening the passage and permitting the lubricant to flow to the bearing, the freedom and 80 quantity of this flow being regulated by the position of the screw which governs the play of the ball. 85

It will be noted that even if particles of dirt 90 be introduced into the cup those of any size will be retained by the narrow opening between the ball and its seat and many of the smaller will be ground or reduced by the rotation of the ball in contact with said seat. 95 To prevent undue wear arising from the grinding action of the ball, this and the plug P are preferably formed of hard steel.

In the use of lubricators upon locomotives it is quite common for the covers of the cups 100

to be shaken off by the jar, whereupon the contents of said cups is thrown out, leaving the bearing dry and often leading to serious heating. With our improved lubricator sufficient oil will be retained within the cage below the openings and above the ball to keep the latter moistened and allow the cup to properly perform its function until the locomotive has reached a suitable stopping-point.

10. It will be seen that while our improved lubricator is inexpensive to construct and contains no elements which can get out of order it will effectually prevent the feed of oil and consequent waste when the elements to be lubricated are not in motion and will deliver the desired quantity as soon as movement is inaugurated.

Having thus described our invention, we claim as new and desire to secure by Letters

20. Patent—

1. A lubricator comprising a cup, a removable plug extending within the cup and being provided with an opening and a surround-

ing seat, a ball coacting with the seat, a cage separably mounted upon the plug and surrounding the ball with its upper wall conforming to said ball, said cage having an extension, and an adjusting member operating in the extension and having an operating-head situated above the top of the cup.

2. In a lubricator, the combination with a receptacle provided with a feed-opening surrounded by a seat, of a ball coacting with the seat, a cage surrounding the seat and having its inner wall above said seat of spherical contour, and a screw threaded through the cage above the seat and having its end curved to conform to the ball.

In testimony whereof we have signed our names to this specification in the presence of 40 two subscribing witnesses.

JOHN H. TOMLINSON.
JAMES M. STARR.
